CLAIM

The ornamental design for urine collection device as shown and described.

DESCRIPTION

FIG. 1 is a perspective view of a urine collection device showing our new design.

FIG. 2 is a top plan view of the urine collection device of FIG. 1.

FIG. 3 is a bottom plan view of the urine collection device of FIG. 1.

FIG. 4 is a first side elevation view of the urine collection device of FIG. 1.

FIG. 5 is a second side elevation view of the urine collection device of FIG. 1.

FIG. 6 is a third side elevation view of the urine collection device of FIG. 1; and,

FIG. 7 is a fourth side elevation view of the urine collection device of FIG. 1.

The portions of the drawing shown in broken lines represent environmental aspects and form no part of the claimed design.
